United States Patent Office.

EDWIN BENNETT, OF BALTIMORE, MARYLAND.

Letters Patent No. 96,869, dated November 16, 1869.

IMPROVEMENT IN FRUIT-JARS.

The Schedule referred to in these Letters Patent and making part of the same.

I, EDWIN BENNETT, of Baltimore, in the county of Baltimore, and State of Maryland, have invented certain Improvements in Fruit-Preserving Jars, of which the following is a specification.

Nature and Objects of the Invention.

My invention relates to the production of an air-tight joint between the mouth-edge of a glass or incorrodible glazed-ware vessel, and the cover or lid of the same material, by making the upper edge of the mouth of the vessel and the upper surface of the rim of the lid or cover to meet in close contact or proximity together, in the same horizontal plane, whilst the under side of the rim of the said lid rests in an annular recess around in the inner side of the mouth of the said vessel; and then covering the annular joint thus produced between them, by an elastic air-proof ring pressed firmly down upon the upper surfaces of the two approximated parts, by means of a clamping-screw cap, or otherwise, so as to cover the said annular joint perfectly air-tight, the object of my invention being to present a glass or glazed-ware surface over the whole interior or fruit-side of the covering, and thus prevent the fruit from coming into contact with the elastic ring, or becoming effected either in flavor or quality by any part of the said interior surface or covering, as well as to make the vessel air-tight.

Description of the Accompanying Drawings.

Figure 1 is a central vertical section of a covered fruit-preserving jar, embodying my invention.

Figure 2 is a plan view of the upper end of the same.

General Description.

A is a glass or glazed-ware jar, having a short neck or elevated mouth, a', the outer side of which latter is screw-cut, its upper edge made flat and even, and its inner side, from the said upper edge to the depth of about a quarter of an inch, more or less, recessed by a sloping-sided groove, 2.

The lid B is made to fit accurately in the sloped recess 2, and of such a thickness around about its edge as will cause the upper surface of the same to come into the same horizontal plane with the surface of the

upper edge of the mouth of the jar, when the said lid is applied.

On the upper side of the lid B there is a raised portion, b', which forms a continuous abutment or shoulder around, and at a short distance from the outer edge of the said lid, as shown in fig. 1.

The ring C is of vulcanized gum-elastic, rectangular in its transverse section, fits around the raised portion b', when applied upon the flat, even surfaces of both the top edge of the mouth of the jar A and the lid B, and covers the annular joint between them, the outside diameter of the said ring C also corresponding with the outside diameter of the mouth-edge of the jar, and its thickness or depth being about twice the height of the raised portion or abutment b' of the lid, (see fig. 1.)

The clamping-screw cap is made in the usual form, open at its top, and of such a depth as will allow it to be screwed down around the neck of the jar, far enough to cause its flanged top to compress the elastic ring C sufficiently to make the annular joint, between the lid and the edge of the mouth of the jar, air-tight, substantially as represented in fig. 1, which figure represents the jar closed air-tight, as intended.

It will be readily seen that this is a very simply-operated and reliable jar for preserving fresh fruits, vegetables, &c., in as pure and perfect a state as when first enclosed, because, as both the jar A and the lid B are made of glass, or of incorrodible glazed-ware, the flavor of the contents cannot be changed or injured thereby, nor can the contents come into contact with, or be affected in flavor by the elastic ring which closes the annular joint air-tight.

Claim.

I claim, as my invention—

A vitreous or earthen jar, provided with an annular interior recess in its neck, and a cover fitting therein, the annular joint between the neck and cover being covered by a packing-ring, held to duty by a screw-cap or similar clamping and retaining-device, substantially as described.
